DESIGN FOR INFANT'S FEEDING BOTTLE HOLDER

Harold J. Edwards, Kansas City, Mo.

Application March 15, 1937, Serial No. 68,168

Term of patent 14 years

To all whom it may concern:

Be it known that I, Harold J. Edwards, a citizen of the United States, residing at Kansas City, in the county of Jackson and State of Missouri, have invented a new, original, and ornamental Design for an Infant's Feeding-Bottle Holder, of which the following is a specification, reference being had to the accompanying drawing, forming part thereof, in which

I claim:

The ornamental design for an infant's feeding-bottle holder substantially as shown.

HAROLD J. EDWARDS,
